UNITED STATES PATENT OFFICE

ODILON CHARETTE, OF FITCHBURG, MASSACHUSETTS

ICE SKATE

Application filed April 29, 1932. Serial No. 608,278.

The invention relates to improvements in ice skates and aims to provide novel and effective provision for holding the skate blades in blade holders, in such manner as to allow either the manufacturer or the user to equip the skates with racing blades, hockey blades, fancy skating blades, etc.

A further object of the invention is to provide a construction in which the opposing forces acting upon the skate blade and the blade holder, during the act of skating, tend to more tightly connect said blade and holder.

Yet another object is to provide blade and holder connecting means necessitating that the blade be first moved forwardly, then rearwardly, and finally downwardly, before it can be detached from the holder. During skating, there is little likelihood that the blade can move in these three directions should it become loose, before the looseness is detected by the skater and there is therefore little danger of losing a blade with the accompanying hazards.

With the foregoing in view, the invention resides in the novel subject matter herein-after described and claimed, description being accomplished by reference to the accompanying drawing.

Fig. 1 is a side elevation showing one form of skate constructed in accordance with the invention.

Fig. 2 is an enlarged longitudinal sectional view.

Fig. 3 is a vertical transverse sectional view on line 3—3 of Fig. 2.

The blade holder 5 is shown as provided with sole and heel plates 6 and 7 connected therewith by posts 8, 9 and 10 which are secured in any desired way to said blade holder, it being intended that said plates be riveted or otherwise secured to a shoe. It will be understood however that any other conventional means could if desired be employed for connecting the blade holder with the

shoe, as my invention is not concerned with features of attachment for connecting blade holder and shoe.

The blade holder 5 is of tubular form, preferably diamond-shaped in transverse section, and throughout the length of its lower side, said blade holder is formed with a longitudinal slot 11. At opposite sides of this slot, the blade holder is provided with longitudinal downwardly projecting flanges 12 disposed in parallel vertical planes. The entire holder 5 with its flanges 12, is preferably formed from rather light sheet metal, and to stiffen it, a reinforcing bar 13, preferably formed from hard wood such as hickory, is snugly fitted in said holder. This reinforcing bar is provided with a straight plane lower side or edge 14 constituting an abutment face which closes the slot 11 and is adapted to tightly abut the straight plane upper edge 15 of a skate blade 16 which is snugly received between the flanges 12. Obviously, this blade may be of any desired type, according to the use to which the skates are to be put.

Any desired number of clamping bolts 17 extend through the flanges 12 and the blade 16, said clamping bolts preferably embodying wing-nuts 18 disposed at one of the flanges 12 while the heads 19 of the bolts are soldered or otherwise secured to the other of said flanges. When the nuts 18 are tightened, the flanges 12 are drawn into tight frictional engagement with the blade 16, whereas said blade is loosened by releasing said nuts. Conventional lock washers 20 are preferably employed for these nuts.

The blade 16 is formed with a plurality of duplicate slots 21 which receive the bolts 17. Each of these slots is provided with a vertical portion 22 opening through the upper edge 15 of the blade 16, with a rearwardly extending portion 23, with a downwardly extending portion 24 and with a forwardly extending portion 25, the latter underlying the

vertical portion 22. The bolts 17 normally occupy the lower extremities of the slots 21, and said extremities are provided with rearwardly inclined upper walls 26 which lie upon the upper sides of said bolts. It thus follows that the opposing forces acting upon the blade 16 and the blade holder 5 during the act of skating tend to always tightly wedge the blade 16 in place with its upper edge 15 resting solidly against the abutment face 14 of the reinforcing bar 13. Thus, under ordinary circumstances, the blade remains tightly in the holder. Should any of the wing nuts loosen sufficiently to allow loosening of the blade in the holder, there is little likelihood of the blade dropping from said holder, for in order to remove said blade, it is necessary that it be moved first forwardly, then rearwardly and then downwardly, and there is little likelihood of the blade so moving should it become loose before its looseness be detected by the skater.

It will be seen from the foregoing that novel provision has been made for carrying out the objects of the invention, and while the details disclosed may be considered as preferred, minor variations may of course be made within the scope of the invention as claimed.

30 I claim:—

1. In a skate, a blade holder having parallel longitudinal blade-straddling flanges and a longitudinal plane straight horizontal abutment face between the upper portions 35 of said flanges, a skate blade snugly received between said flanges and having a straight plane upper edge contacting with said abutment face, and bolts passing through said flanges, said blade being provided with slots 40 opening through its upper edge and receiving said bolts, said slots being directed upwardly and forwardly and provided with rearwardly inclined walls lying on the upper sides of said bolts, whereby the opposing 45 forces acting on said blade holder and said blade during skating, tend to wedge said blade into tight engagement with said abutment face.

2. In a skate, a blade holder having a plane 50 downwardly presented blade abutment and parallel longitudinal blade-straddling flanges projecting downwardly beyond said abutment, a bolt extending through said flanges, and a skate blade snugly received between 55 said flanges and having a plane upper edge abutting said abutment, said blade having a slot receiving said bolt, said slot having a vertical portion opening through the upper edge of the blade and a poly-directional portion, the latter extending first rearwardly, 60 then downwardly, and then forwardly and downwardly under said vertical portion, said bolt being normally disposed in the lower extremity of said slot.

65 3. A skate blade provided with bolt-receiving

slots opening through its upper edge, said slots being directed upwardly and forwardly and provided with rearwardly inclined walls to lie upon the slot-received bolts.

4. A skate blade provided with bolt-receiving slots, each slot having a vertical portion opening through the upper edge of the blade and a poly-directional portion, the latter extending first rearwardly, then downwardly, and then forwardly and downwardly under said vertical portion.

In testimony whereof I affix my signature.

ODILON CHARETTE.
